DESIGN FOR A COCKTAIL SHAKER

Solomon Forman, Brooklyn, N. Y., assignor to Forman Bros. Inc., Brooklyn, N. Y., a corporation of New York

Application December 23, 1935, Serial No. 60,245

Term of patent 3½ years

To all whom it may concern:

Be it known that I, Solomon Forman, a citizen of the United States and resident of Brooklyn, county of Kings, and State of New York, have invented a new, original, and ornamental Design for a Cocktail Shaker, of which the following is a specification, reference being had to the accompanying drawing, forming part thereof.

In the drawing,—

showing my new design.

Figure 2 is a plan view of the same.

I claim,—

The ornamental design of a cocktail shaker as shown.

In testimony whereof, I have hereunto set my hand on this 18th day of December, 1935.

SOLOMON FORMAN.
